Attorney.

UNITED STATES PATENT OFFICE.

FRANK WAGNER, OF LOS ANGELES, CALIFORNIA, ASSIGNOR TO PITTSBURGH VALVE
AND FITTINGS COMPANY, OF BARBERTON, OHIO, A CORPORATION OF NEW JERSEY.

DESIGN FOR A LIGHTING FIXTURE.

Application filed October 24, 1927. Serial No. 23,856. Term of patent 7 years.

To all whom it may concern:

Be it known that I, FRANK WAGNER, a citizen of the United States, residing at Los Angeles, in the county of Los Angeles and State of California, have invented a new, original, and ornamental Design for Lighting Fixtures, of which the following is a specification, reference being had to the accompanying drawing, forming a part thereof.

I claim:

The ornamental design of a lighting fixture as shown.

FRANK WAGNER.
